UNITED STATES PATENT OFFICE.

EDWARD E. ROSE, OF SWISSVALE, AND ORA A. COLBY, OF WILKINSBURG, PENNSYLVANIA, ASSIGNORS TO WESTINGHOUSE ELECTRIC AND MANUFACTURING COMPANY, A CORPORATION OF PENNSYLVANIA.

ELECTRICAL CONNECTOR.

1,241,556.

Specification of Letters Patent.

Patented Oct. 2, 1917.

Application filed November 5, 1913. Serial No. 799,372.

To all whom it may concern:

Be it known that we, EDWARD E. ROSE, a citizen of the United States, and a resident of Swissvale, in the county of Allegheny and State of Pennsylvania, and ORA A. COLBY, a citizen of the United States, and a resident of Wilkinsburg, in the county of Allegheny and State of Pennsylvania, have invented a new and useful Improvement in 10 Electrical Connectors, of which the following is a specification.

Our invention relates to electrical connectors, and it has special reference to detachable plug-connectors for use in curling-irons and the like.

The object of our invention is to provide a device of the above-indicated character which shall be simple, durable and inexpensive in construction and reliable and convenient in operation.

Heretofore, the detachable plug-connectors provided for embodiment in electrical curling-irons and other similar apparatus have been relatively expensive and more or less complicated or delicate in construction, thereby entailing high cost of maintenance and unsatisfactory operation.

According to our invention, we provide a swiveling detachable plug-connector for the above-mentioned purposes that embodies features which collectively obviate the disadvantages hereinbefore mentioned.

In the accompanying drawing, Figure 1 is a view in elevation, with parts broken away, of an apparatus embodying an electrical connector constructed in accordance with our invention; and Fig. 2 is a view, partially in longitudinal section, on the line II-II of Fig. 1 and partially in elevation 40 at right angles to the view of Fig. 1.

Referring to the drawing, the electrical connector shown comprises a pair of oppositely-disposed and suitably chambered supporting parts or shells 2, a pair of sets 3 and 4 of contact members disposed within the shells 2, and a plurality of resilient rings 5 and 6 for detachably joining the shells 2.

The supporting shells 2 are of insulating and preferably of molded material, and are severally provided with portions 2^a and 2^b of relatively small and of larger diameter which respectively have relatively shallow

and deeper internal recesses 7 and 8. The shells 2 also have a plurality of spaced external grooves 9 and 10 that are respectively 55 adapted to receive the resilient clamping rings 5 and 6. A centrally-located end opening, comprising a plurality of V-shaped grooves 11, is provided in the assembled shells 2 for receiving and frictionally engaging supply conductors 12. A relatively narrow and deep internal groove 13 is disposed intermediate the ends of the smaller portion 2^a of the shells 2 for a purpose hereinafter specified.

The set 3 of contact members comprises a pair of longitudinally-aligned and suitably curved resilient contact clips or jaws 14 and 15 severally having corresponding ends suitably attached to the shells 2 within or adjacent to the recesses 8 in the portions 2^b of the shells 2, the jaw 14 being made longer than the jaw 15 and its attached end being connected to one of the supply conductors 12. A supporting band 16 of conducting 75 material is disposed around the contact members 14 and 15 and within the groove 13.

The set 4 of contact members comprises a relatively short forked resilient contact clip or jaw 17 that is longitudinally set at 80 right angles to and concentrically disposed within the set 3 of contact members. The unforked end 18 of the contact jaw 17 is offset and is suitably attached to the second supply conductor 12 and to one of the shells 85 2 within the recess 13. It will be understood from the foregoing description that the sets 3 and 4 of contact members are independent and are respectively adapted for connection to supply lines of opposite polarity.

The clamping rings 5 and 6 are preferably of piano wire, or the like, and serve to detachably assemble the shells 2, as hereinbefore described.

A heating-device, here shown for illustrative purposes in association with the connector as a curling iron, embodies a suitable heater, a hollow handle 21, terminal members 22 and 23 for the heater that extend into the hollow space in the handle, and my connector inserted within the handle 21 and having its sets of contact members 3 and 4 respectively adapted to engage;

and rotate or swivel around, the terminal members 22 and 23.

The handle 21 has a centrally-located, relatively large internal recess within which the small portions 2^a of the shells 2 are adapted to fit and a contiguous recess 25 of smaller diameter, within which is disposed a ring 29, thereby forming an internal shoulder 26, for a purpose to be specified. The terminal members 22 and 23 extend into the large recess and are concentrically related, the outer member constituting a suitably-shaped shell and the inner member constituting a rod insulated from and projecting 15 beyond the outer shell.

The outer terminal member 22 has an external groove 27 near its inner end and an external flange 28 intermediate its ends. In operative position, the external flange 28 abuts against the internal shoulder 26 and the groove 27 falls within the recess 25. The ring 29 is disposed around the terminal member 22 within the recess 25 and has a plurality of threaded openings disposed in 25 alinement with the groove 27 and which are adapted to register with corresponding openings 31 in the handle 21. A plurality of screws 32 extend through the openings 31 and engage the groove 27, thereby preventing 30 movement of the heater.

It will be noted that the above-described construction allows of a swiveling of the curling-iron with respect to the plug-connector. By holding stationary the portion 35 2^b of the connector and imparting a rotative movement to the handle 21, this swiveling action, which is very desirable in the use of curling-irons, may be readily obtained and without breaking the electrical connections, since the terminal members 22 and 23 turn smoothly and easily within the sets of contact members 3 and 4, respectively.

We do not wish to be restricted to the specific structural details herein set forth, but desire that only such limitations shall be imposed as are indicated in the appended claims.

We claim as our invention:

1. An electrical connector comprising oppositely-disposed supporting parts of insulating material each having a plurality of external grooves and a relatively shallow and a deeper internal recess, a plurality of contact clips severally having one end attached within the deeper recesses for connection to an external source of electrical energy, and a plurality of clamping rings detachably disposed in the said grooves.

2. In an electrical apparatus, the combination with a plurality of terminal members, one of which has an external groove therein, of an electrical connector comprising a plurality of sets of concentrically disposed and independent resilient contact members, said contact members being

adapted for rotative engagement with the said terminal members and one set of the said contact members being provided with bent ends for engaging the groove in one of the terminal members to secure the same together. 70

3. In an electrical apparatus, the combination with a base member, of a plurality of concentrically related terminal members, means for securing the terminal members 75 in the base member in any desired position, and coöperating contact members for engaging the said terminal members.

4. In an electrical apparatus, the combination with a base member, of a plurality 80 of concentrically related terminal members, one of which has a circumferential groove therein, means for adjustably securing the terminal members in the base member, and coöperating concentrically disposed contact 85 members for engaging the said terminal members, the said contact members being adapted to grip the groove in the terminal member to retain the same in engagement.

5. In an electrical apparatus, the combination with a base member having an internal recess therein, of concentric contact members disposed within the recess, an annular member disposed within the recess and around the contact members, and a plurality of screws disposed in the said base member for extending through the annular member to retain the contact members in 90 any desired position.

6. In an electrical apparatus, the combination with a base member having an internal opening with a shoulder therein, of a plurality of concentrically related terminal members disposed within the opening in the base member, one of the terminal 100 members being provided with an external groove and a projection for engaging the said shoulder, an annular member surrounding the said terminal members, and radially adjustable means extending through the 105 said annular member and the said base member for engaging the groove in the terminal member to retain the same in any predetermined position.

7. An electrical connector comprising oppositely disposed supporting parts of insulating material each having a relatively shallow and a deeper internal recess, and two pairs of substantially flat contact members severally having one end attached 120 within the deeper recesses for connection to an external source of electrical energy, the normal distance between the lower ends of the respective contact members of each pair being relatively different. 115

8. An electrical connector comprising oppositely disposed supporting parts of insulating material each having a relatively shallow and a deeper internal recess, and two pairs of substantially flat contact mem- 130

bers severally having one end attached within the deeper recesses for connection to an external source of electrical energy, the said pairs of contact members being disposed substantially at right angles to each other.

5 In testimony whereof, we have hereunto

subscribed our names this 31st day of Oct., 1913.

EDWARD E. ROSE.
ORA A. COLBY.
